UNITED STATES PATENT OFFICE.

JOHN H. LONDICK, OF DEARBORN, MICHIGAN.

WINDOW CONTROL AND SILENCER.

Application filed January 11, 1928. Serial No. 80,457.

This invention relates to a window control and silencer, and has special reference to that class of devices especially designed for the doors and bodies of automobiles, truck cabs, car windows and such places where a pane of glass, sash or other closure member is adapted to be adjusted primarily for ventilating purposes. My device may also be classified with those lifting devices wherein the retractile force of a spring is utilized for lifting or closing a pane of glass or closure member which is adapted to be manually opened.

My invention, in its broadest aspect, involves a compact and durable device that may be easily and quickly mounted in the window sill of a door frame, body wall or other structure for automatically lifting a pane of glass, sash or closure member that is slidable in the door, wall or structure and is adapted to completely close an opening in the door, wall or structure.

My invention aims to provide a window control and silencing device wherein a spring motor is utilized for lifting a pane of glass or other transparent material to a closed position, and associated with the spring motor is a control mechanism that may be characterized in the following particulars.

First, the control mechanism includes an anti-rattling device by which the pane of glass is clamped in any position to which it may be adjusted, so that the glass cannot rattle in its frame or sash and is more or less cushioned against breakage incident to vehicle operations.

Second, the control mechanism includes a brake for the spring motor with the brake operable in synchronism with the anti-rattling device so that there may be a co-operation of the brake and anti-rattling device for positively holding the pane of glass against accidental movement and the spring motor against accidental operation.

Third, the control mechanism includes means by which an initial opening movement may be imparted to the pane of glass so that it may be conveniently gripped and further manually opened, such operation placing the spring motor in active condition

for instant use when it is desired to close the pane of glass.

There are certain novel structural details entering into my invention and these will be hereinafter specifically described and then claimed. Reference will now be had to the drawing wherein

Fig. 1 is a view of the inner side of an automobile door having a slidable pane of glass, the door being broken away to show my mechanism in the well of the door;

Fig. 2 is a vertical cross sectional view of the same;

Fig. 3 is a detail sectional view showing a portion of the control mechanism relative to a bottom rail of the pane of glass;

Fig. 4 is a perspective view of a spring motor showing a cam member in a clamping position;

Fig. 5 is a vertical sectional view, on an enlarged scale, of a portion of the door showing the control mechanism and silencer, with the mechanism in a clamping position;

Fig. 6 is a detail sectional view of the portion of the control mechanism relative to the bottom rail of the pane of glass;

Fig. 7 is a plan of the control mechanism removed from the door;

Fig. 8 is a diagrammatic view of a cam member illustrating its functions, and

Fig. 9 is a detail sectional view of a portion of the control mechanism relative to the bottom rail of the pane of glass showing the manner in which the pane of glass is held in a raised closed position.

In the drawings, the reference numeral 1 denotes a door, wall or other structure having a well 2 and an opening 3. The door has its top and bottom rails provided with grooves or ways 4 and 5 for the top and side edges of a pane of glass 6, sash or closure member which is slidable in the door frame and shiftable in and out of the well 2, the pane of glass when raised providing a transparent closure for the opening 3.

For the convenience of illustration and to somewhat conform to modern practice, the door 1 has been shown as made of metal, with a slotted sill 7 through which the pane of glass 6 may be shifted. The inner wall 8

of the door has been shown as provided with an opening 9 for the convenience of installing my controlling mechanism in the well 2, the opening 9 being closed by door 6 interior trimmings (not shown). It is to be understood, however, that for other types of doors and installations of my mechanism that it may not be necessary to provide the opening 9 nor the specific fastening means 10 which I employ for retaining the mechanism within the well 2.

The reference numeral 10 denotes a supporting plate which may be stamped and pressed to form a cylindrical casing 11 for a spring motor, and said plate is cut and stamped, as at 12 to provide outstruck hook shaped lugs 13 which may be mounted in openings provided therefor in the door wall 8, above the opening 9, which is adapted to 20 receive the supporting plate 10 and permit of said plate being shifted up into the well and suspended by the hook shaped lugs 13 against the inner face of the door wall 8.

Fixed within the casing 11 is a stud 14 and 25 rotatable on said stud and shiftable longitudinally thereof is the hub portion 15 of a drum 16 having a single side wall affording an annular brake engaging surface 17. The periphery or rim 18 of the drum 16 has an 30 annular flange or shoe 19 adapted to frictionally bear against the inner face of the door wall 8 and retard rotation of the drum. The rim 18 has two transverse slots 20 and 21. Anchored in the slot 20 of the rim is 35 the end 23 of a coiled band spring 24 which has its inner end anchored, as at 25, on the stationary stud 14, so that the spring may be coiled about the stud when the drum 16 is revolved in a spring winding direction. The 40 spring 24 and its drum 16 constitute a spring motor enclosed by the casing 11 in cooperation with the door wall 8.

Anchored in the transverse slot 21 of the drum rim 18 is the end 22 of a flexible lifting member 26, preferably in the form of a strap wound on the drum with the outer end of the strap extending through an opening 27 provided therefor in the casing 11. The outer end of the lifting member 26 is 50 suitably attached, as at 28 to the lower end 29 of an angularly disposed arm 30, said arm being disposed in a lateral direction to one side of the member 26 and in an outward direction towards the pane of glass 6. The upper end of the arm 30 is spot welded or otherwise secured to a channel rail 31 mounted on the lower end of the pane of glass 6, and said channel rail is provided with an outstruck lock lug 32 for a 55 purpose that will hereinafter appear. The pane of glass 6 may be cushioned within the channel rail 31 and said channel rail has a rolled edge 33 and an outstruck ledge 34.

The casing 11 is formed with a bearing

or housing 35 for an arbor 36 which may 65 be partially rotated or rocked in the bearing 35, said arbor extending through an oblong opening 37 in the door wall 8 and having its outer end provided with a detachable crank or hand piece 38 by which 70 the arbor may be conveniently rocked. In addition to the arbor being rotative in its bearing, it is reciprocable with such longitudinal play of the arbor for a purpose that will hereinafter appear.

Mounted on the inner end of the arbor 36 is a cupped cam member 39 having a cam surface 41. The opposite flat face cam member 39 is adapted to engage a brake member 42 loosely mounted in an opening 43 provided therefor in the casing 11, and said brake member bears against the brake surface 17 of the drum 16 so that said drum may be crowded towards the door wall 8 and clamped between the brake member 42 85 and the door wall. The brake member 42 will have a braking action against the drum 16 and the annular shoe 19 of said drum will have a braking action against the door wall 8 which being stationary will retard 90 and cause the cessation in the operation of the spring motor when the brake member 42 is actuated.

The casing 11 is provided with two holders 43 and 44, both preferably outstruck 95 from the wall of the casing 11. In addition to these holders there is a set of outstruck guide lugs 45 which cooperate with the holder 44 in correctly positioning a clamping member 46 relative to the casing 100 11 and the pane of glass 6. Adjacent the lower end of the clamping member 46 is a bowed portion 47 engaged by a comparatively flat compression spring 48 suitably mounted in the holder 43 and this spring 105 is adapted to hold the clamping member 46 in a retracted position, that is, normally in engagement with the cam member 39. The upper end of the clamping member 46 is also bowed, as at 49 and provided with a yieldable or friction shoe 50, made of leather, rubber, felt or any suitable material, that may be conveniently retained on the clamping member 46 by outstruck lugs 51 of said member. The shoe 50 serves functionally as 110 a buffer and engages the inner face of the pane of glass 6, as best shown in Fig. 5, to hold the outer face of the pane of glass against a stationary buffer 52 carried by a bracket 53 attached to the under or inner side of the sill 7. The two buffers cooperate as a silencer or anti-rattling device to prevent the pane of glass from vibrating in its frame or sash, and these buffers also serve as braking or clamping means for retarding movement of the pane of glass and holding it in adjusted position.

The cam member 39 is adapted to engage

a pressed out portion or boss 54 on the upper inner face of the clamping member 46, and said cam member is formed with a peripheral crank 55 having an antifrictional 5 roller 56 adapted to engage the ledge 34 of the sash rail 31, as best shown in Fig. 7. The cam member 39 has another portion in the form of a stop lug 57 adapted to engage the casing 11, as best shown in Fig. 4, said 10 stop lug being connected by a coiled retractile spring 58 to the supporting plate 10.

When the pane of glass 6 is fully raised or closed the flexible lifting member 26 is almost in an unwound condition on the 15 spring motor and to a great extent the force of the spring 24 has been expended, yet retaining sufficient retractile force to hold the lifting member 26 partly wound about the drum 18 with the upper edge of the pane 20 of glass 6 in the upper groove or way 4 of the door frame.

Considering the position of the arbor 36, as shown in Fig. 5, where the pane of glass is in a clamped position and the cam member 25 39 engaging the boss 54 of the clamping member 46 forcing the shoe 50 against the pane of glass 6 and said pane of glass against the buffer 52. In addition to this 30 clamping action of the pane of glass there is the clamping action for the spring motor which is brought about by the brake member 42 bearing against the drum 16 and said drum against the door wall 8. In other words, the shoe 50 engaging the pane of 35 glass 6 holds the boss 54 so that the cam member 39 may be wedged between the boss 54 and the brake member 42. This is permissible by reciprocal cam supporting arbor 36, and the position of the cam member 40 39 is defined by the stop lug 57 engaging the casing 11, as shown in Fig. 4.

When it is desired to lower the pane of glass 6 from a full closed position and place it in a partly lowered position, as in Fig. 5, the crank or hand piece 38 is gripped and turned in a counterclockwise direction considering Fig. 8. Such rocking of the arbor 45 permits retraction of the clamping member 46 under the influence of the spring 48, but the force of the spring is not sufficient to effect braking of the spring motor and simply retains the boss 54 in engagement with the cam member. As the cam member 50 is rotated the spring 58 is stressed, the clamping member 46 releases the pane of glass 6 and it is to be noted that the antifrictional roller 56 is in engagement with the ledge 34 of the bottom rail 31 of the pane of glass, so that as the cam member 55 60 39 is rotated by the arbor 36 the pane of glass to be initially moved a predetermined distance. This has been indicated in Figs. 1 and 2, by the dash lines representing the pane of glass 6 as partially open and the 65 gap or opening between the upper edge of

the pane of glass 6 and the door frame 1 is of sufficient area to permit of a hand gripping the upper edge of the pane of glass to lower it in the frame. The initial movement of the pane of glass has not conditioned or materially wound the spring motor, so the hand may be removed from the hand piece 38 and placed on the upper edge of the pane of glass to lower it to a full open position. Such adjustment will wind 70 and condition the spring motor. The retractile force of the spring 58 restores the cam member 39 to a normal or neutral position, and as the pane of glass reaches a lowered position, the same hand on the upper edge of the glass is brought in proximity to the hand piece 38 which may be flipped clockwise to cause the cam member 39 to actuate the clamping member 46 and the brake member 42 whereby the pane of 75 glass and the spring motor are held.

Reverting to the lowering movement of the pane of glass 6, the flexible lifting member 26 is unwound from the drum 18 of the spring motor and the spring 24 is wound up, thus placing the spring motor in condition 80 for activity when the pane of glass 6 is to be raised.

The arbor 36 and the drum 18 are reciprocal relative to the bearing 35 and the stud 14 respectively, so that the cam member 39 may wedge itself between the boss 54 and the brake member 42 while the drum 18 engages the door wall 8 for a braking action.

The cam member 39, as shown in Fig. 8, 95 is designed so that a clamping portion 40 of the cam surface is engageable with the boss 54 for holding the pane of glass lowered or in any intermediate position. When the cam member 39 is turned in a clockwise 100 direction, after the pane of glass is raised and in a closed position, the boss 54 engages a locking portion 54^a of the cam. The clamping member 46 is shifted against the action of the spring 48 and the shoe 50 105 placed against the back lug 32 of the rail 31 and under said rail, so that the pane of glass is locked in a closed position. This is accomplished without the boss 54 reaching the peak of the cam surface, the remaining portion 110 of the cam being for any inequalities of manufacture or difference of thickness of the pane of glass. Obviously the pane of glass cannot accidentally lower or rattle on account of the combined locking and clamping 115 120 action of the clamping member 46.

It will be noted that the pane of glass must be fully lowered before being placed in any intermediate position. Upon being lowered, the finger piece 38 may be manipulated to allow the pane of glass to rise a desired distance. Turning the finger piece in one direction releases the glass and turning in a reverse direction clamps the glass. This right or left turning and the arrange- 125 130

ment of the cam member are optional with a manufacturer to meet a desired condition or modus operandi.

From the foregoing it will be observed that the greater part of my mechanism is made from sheet metal stampings and is a bench assembled structure that may be easily and quickly installed relative to a closure that is to be adjusted and clamped in adjusted position, but while the parts have been shown in their preferred form as successively used, yet it is to be understood that the structural elements are susceptible to such changes as are permissible by the appended claims.

What I claim is:—

1. In a window control mechanism for a slidably mounted pane of glass adapted to be lowered by hand, and wherein a spring motor having its axis of rotation at an angle to said pane of glass is adapted to be conditioned by a lower movement of the pane of glass to raise the pane of glass, a motor controlling means interposed between said motor and said pane of glass operable to engage and hold the pane of glass in an adjusted position and produce a braking action against said motor.

2. In a window control mechanism for a slidably mounted pane of glass adapted to be lowered by hand, and wherein a spring motor having its axis of rotation at an angle to said pane of glass is adapted to be conditioned by a lowering movement of the pane of glass to raise the pane of glass;—a motor controlling means interposed between said motor and said pane of glass and having a portion thereof operative to impart initial movement to the pane of glass so that it may be further moved by hand, said motor controlling means being operable to engage and hold the pane of glass in an adjusted position and produce a braking action against said motor.

3. A window control mechanism as called for in claim 1, wherein said motor controlling means includes a shiftable drum, a brake member, and a manually actuated cam member.

4. In a window control mechanism for a slidably mounted pane of glass, adapted to be lowered by hand and raised by means conditioned by the lowering movement of the pane of glass, means adapted to clamp the pane of glass, and a cam member operable between said glass raising means and clamping means to control the operation of each.

5. A window control mechanism as called for in claim 4, wherein a portion of said cam member is operative to initially slide said pane of glass to facilitate its movement by hand.

6. A window control mechanism as called for in claim 4, wherein the clamping means

includes a buffer at one side of the pane of glass, and a clamping member at the opposite side of the glass operable by said cam member.

7. In a window regulating mechanism 70 wherein a pane of glass is slidably mounted in a frame and movable through a sill and in and out of a well below said sill, and wherein a spring motor in the frame well having its axis of rotation at an angle to said pane of glass is adapted to lift the pane of glass and permit of it being manually lowered; buffers in the frame well engaging opposite sides of the pane of glass and adapted to hold the pane of glass in adjusted position, and means controlling one of said buffers and said spring motor whereby said pane of glass may be released for movement either by hand or by said spring motor.

8. A window regulating mechanism, as 85 called for in claim 7, wherein a portion of said means is operable to impart initial movement to the pane of glass to permit of it being further manually moved.

9. In a window regulating mechanism 90 wherein a pane of glass is slidably mounted in a frame and movable through a sill and in and out of a well below said sill, and wherein the spring motor in the frame well having its axis of rotation at an angle to 95 said pane of glass is adapted to lift the pane of glass and permit of it being manually lowered;—buffers in the frame well engaging opposite sides of the pane of glass and adapted to hold the pane of glass in adjusted position, means controlling one of 100 said buffers and said spring motor whereby said pane of glass may be released for movement either by hand or by said spring motor, and means carried by the pane of glass and engageable by one of said buffers to hold said pane of glass in a raised closed position.

10. A window regulating mechanism as 110 called for in claim 7, wherein a spring enclosing drum is shiftable axially of the spring motor, so that the operation of the spring motor may be controlled.

11. In a window regulating mechanism 115 wherein a pane of glass is slidable in a frame and into and out of a well in the frame, and wherein a spring motor is adapted to lift the pane of glass to a closed position and permit of the pane of glass being manually lowered;—means for controlling the movement of the pane of glass, said means comprising a stationary buffer, a movable buffer to cooperate with the stationary buffer in holding the pane of glass in adjusted position, means carried by the pane of glass engageable by the movable buffer adapted to hold the pane of glass in a closed position, and a cam member for shifting said movable buffer and controlling said spring motor.

12. In a window regulating mechanism wherein a pane of glass is slidable in a frame and into and out of a well in a frame, and wherein a spring motor is adapted to lift the pane of glass to a closed position and permit of the pane of glass being manually opened;—and means for controlling the movement of the pane of glass, said means comprising a stationary buffer, a movable buffer to cooperate with the stationary buffer in holding the pane of glass in adjusted position, means carried by the pane of glass engageable by the movable buffer adapted to hold the pane of glass in a closed position, and a cam member operable to have a portion thereof impart initial lowering movement to said pane of glass so that it may be further manually moved, said cam member being operable to shift said movable buffer and control said spring motor.

13. In a window regulating mechanism wherein a pane of glass is slidable in a frame and into and out of a well in a frame, and wherein a spring motor is adapted to lift the pane of glass to a closed position and permit of the pane of glass being manually opened;—means for controlling the movement of the pane of glass, said means comprising a stationary buffer, a movable buffer to cooperate with the stationary buffer in holding the pane of glass in adjusted position, means carried by the pane of glass engageable by the movable buffer adapted to hold the pane of glass in a closed position, a cam member for shifting said movable buffer and controlling said spring motor, and a manually operated arbor supporting said cam member and adapted to be turned in one direction to an active position by hand and automatically turned in an opposite direction to a neutral position when released.

14. In a window regulating mechanism wherein a pane of glass is slidable in a frame and into and out of a well of the frame, and wherein a spring motor in the frame well is adapted to be conditioned to raise the pane of glass when it is lowered by hand;—means for controlling said motor, said means comprising a spring enclosing drum shiftable axially of said motor and relative to a well wall for controlling the operation of the spring motor, a flexible member on said drum adapted for raising the pane of glass and adapted to be wound on the drum when the pane of glass is manually lowered, a brake member extending into said casing, and manually controlled means engageable with said brake member to cause it to engage said drum and shift said drum for a braking action of said spring motor.

15. A window regulating mechanism as called for in claim 14, wherein said manually controlled means is operative to pro-

duce a clamping action on the pane of glass to hold said pane of glass in adjusted position.

16. A window regulating mechanism as called for in claim 14, further characterized by a ledge at the lower end of the pane of glass engageable by said manually controlled means which includes a cam member having a portion thereof engageable with the ledge to have an initial lowering movement imparted to the pane of glass to facilitate further manual movement.

17. In a window wherein a sash is adapted to be lowered by hand and automatically raised to a closed position;—means adapted to hold said sash in a closed position, said means comprising a clamping member, a rotatable member adapted to actuate said clamping member and in one position is adapted to cause said clamping member to engage under a portion of said sash to hold it closed, and when said rotatable member is turned to another position cause said clamping member to engage another portion of said sash to impart initial lowering movement to said sash.

18. A window construction as called for in claim 17, further characterized by said rotatable member in another position causing said clamping member to hold said sash in an adjusted position.

19. Sash regulating means comprising a rotatable member reciprocable to and from the face of a sash, a crank carried by said member adapted to engage the sash to initially lower it, a clamping member operable by said rotatable member for clamping said sash in adjusted position, said clamping member being operable by said rotatable member to engage under said sash to hold it in a raised position.

20. Sash regulating means comprising an arbor, a cam member on said arbor, and a clamping member operable by said cam member to hold a sash in adjusted position, said clamping member being operable by said cam member to extend under the sash to hold it in a closed position.

21. Sash regulating means comprising a manually operable cam member, a clamping member, means carried by said cam member and engageable with the lower end of a sash for lowering said sash to provide an opening at the upper end of said sash, and means holding said clamping member normally in engagement with said cam member so that said cam member may actuate said clamping member to hold the sash in adjusted position.

22. In a window sash regulator wherein the sash must be manually shifted by one hand, to a full lowered position before the same hand can be used to secure the sash in a partly closed position;—means adapted

for locking the sash in a raised closed position, initially lowering the sash, and clamping the glass in an intermediate position, said means comprising a clamping member engageable under under the lower end of the sash to secure it in a raised closed position.

23. A window sash regulator as called for in claim 22, further characterized by a cam member adapted to actuate said clamping member and also engage the lower edge of the sash to initially lower it.

In testimony whereof I affix my signature.
JOHN H. LONDICK.
